His Attorney

UNITED STATES PATENT OFFICE.

SAMUEL M. LUCAS, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

Application filed September 29, 1922, Serial No. 591,252. Renewed December 2, 1926.

My invention relates to railway signaling, and particularly to signaling of the type comprising light signals controlled by three-position relays.

5 One feature of my invention is the provision of a novel means for preventing momentary lighting of the stop lamp in a system of this character when the relay moves from one extreme position to the other.

10 I will describe one form of system embodying my invention, and will then point out the novel features thereof in claims.

The accompanying drawing is a diagrammatic view showing one form of signaling system embodying my invention.

15 Referring to the drawing, the reference characters K and L designate the track rails of a railway over which traffic normally moves in the direction indicated by the arrow. These rails are divided by insulated joints 20 into a plurality of track sections A—B, B—C, etc. Each track section is provided with a source of track circuit current which, as here shown, is a secondary winding 11 of a transformer designated by the reference character U with an exponent corresponding to the location, this secondary being connected across the rails at the exit end of the section. Interposed between this 20 secondary winding 11 and the upper rail of each section is an impedance 10. One function of this impedance is to limit the current output of the transformer U to a safe value when short circuited by a train in the section.

25 Each section is also provided with a track relay which is designated by the reference character X with an exponent corresponding to the location; each of these relays comprises a track winding 2 connected

30 across the rails adjacent the entrance end of the section, and a local winding 1 constantly supplied with alternating current from a transmission line D which is fed by a generator J. It will thus be seen that each 35 track section is provided with a track circuit comprising a transformer secondary 11 and a track relay winding 2.

40 Each relay X comprises two contact fingers 17 and 18 which are controlled by the

45 currents in the relay windings 1 and 2. Each relay is responsive to reversals of the relative polarity of the current supplied to the track winding 2. When current of normal relative polarity is supplied to this winding the relay is energized in what I will term 50 "normal" direction, and when thus energized the contact fingers 17 and 18 are swung to the left, so that contacts 17—3 and 18—6 are closed; these contacts I will therefore term the "normal" contacts of the relay. 55 When the track winding 2 is supplied with current of reverse relative polarity, the relay is energized in what I will term "reverse" direction, and when thus energized contact fingers 17 and 18 are swung to the right, so 60 that contacts 17—5 and 18—8 are closed; these contacts are accordingly termed the "reverse" contacts of the relay. When the track winding 2 is de-energized, contact fingers 17 and 18 occupy intermediate positions wherein the back contacts 17—4 and 18—7 are closed.

65 Each track section is provided with means for supplying current of one relative polarity or the other to the track rails of the section, and as here shown, this is accomplished by controlling the polarity of the current supplied to the primary winding of each transformer U. Referring particularly to transformer U^A, the middle point of the primary 12 of this transformer is constantly connected by a wire 26 with the right-hand terminal of the secondary 15 of a transformer T^A, and the left-hand terminal of secondary 15 is connected with one end or 70 the other of primary 12 according as relay X^A is energized or de-energized. When relay X^A is de-energized, so that its back contact 18—7 is closed, the left-hand terminal of secondary 15 is connected with the right-hand terminal of primary 12 through wires 75 23 and 24, back contact 18—7 on relay X^A and wire 25. The current which is then supplied to the track rails of the section A—B is of reverse relative polarity. When track relay X^A is energized in normal direction so 80 that contact 18—6 is closed, the left-hand terminal of secondary 15 is connected with

the left-hand terminal of primary 12 through wires 23 and 24, contact 18-6, wires 28 and 27, to primary 12. When relay X^A is energized in reverse direction the path is the same as that just traced except that it includes reverse contact 18-8 and omits wire 28. With relay X^A energized in either normal or reverse direction, the current which is supplied to the track rails of section A-B will be of normal relative polarity.

Each track section is provided with a signal designated by the reference character S with an exponent corresponding to the location, each of which signals comprises three lamps G, Y and R, adapted when lighted to indicate "Proceed", "Caution" and "Stop", respectively. Each signal is controlled by the associated relay R, the circuits being as follows:

20 Considering signal S^B , for example, the circuit for the proceed lamp G passes from the secondary 15 of transformer T^B , through wires 23 and 29, normal contact 17-3 of relay X^B , wire 30, lamp G, and wires 21 and 22 to the secondary 15 of transformer T^B . This circuit is, of course, closed only when relay X^B is energized in the normal direction. The circuit for the caution lamp Y of signal S^B is from the secondary of transformer T^B through wires 23 and 29, reverse contact 17-5 of relay X^B , wire 31, lamp Y, and wires 21 and 22 to the secondary of transformer T^B . This circuit is closed only when relay X^B is energized in reverse direction. The circuit for the stop lamp R of signal S^B is from the secondary of transformer T^B through wires 23 and 29, back contact 17-4 of relay X^B , wire 32 and impedance 9, wire 33, lamp R and wires 21 and 22 to the secondary of transformer T^B . This circuit is closed only when track relay X^B is de-energized.

As shown in the drawing, the track circuit A-B is occupied by a car or train V, so that 45 relay X^B is de-energized with the result that current of reverse relative polarity is supplied to the rails of section B-C. Track relay X^C is therefore energized in reverse direction, so that the caution lamp Y of signal 50 S^C is lighted.

I will now assume that the car or train V passes out of section A-B and into the section immediately to the left of point A. As this car or train leaves section A-B track 55 relay X^B will become energized in reverse direction, thereby causing current of normal relative polarity to be supplied to the rails of section B-C with the result that the contact fingers of relay X^C will shift from their 60 reverse positions to their normal positions, so that lamp Y of signal S^C will become extinguished and lamp G of this signal will become lighted.

It will be noted that during the reversal 65 of the relay contacts just referred to, the

back contact 17-4 will be closed momentarily, so that the circuit for the stop lamp R of signal S^C is momentarily closed. In the absence of any preventive means this would result in the momentary lighting of the stop lamp R, that is, the signal would momentarily indicate stop. This is undesirable, and to prevent such momentary lighting of the lamp R I have included in series with this lamp the impedance 9 which may 70 be, for example, a resistance, a reactance or a condenser. As here shown it is a reactance. The value of this impedance is such that the amount of current supplied to the lamp R during the brief interval in which contact 17-4 is closed is not sufficient to bring this lamp up to full illumination. The lamp R is preferably a tungsten filament lamp which, as is well understood, has a lower resistance when cold than when it 75 is hot, and the value of the impedance 9 is preferably such that the initial rush of current in the lamp R when contact 17-4 closes is substantially the same as the amount of current taken by this lamp when the lamp 80 is hot. By proportioning the elements of the lamp R in this manner the lamp will not be lighted during the momentary closure of contact 17-4 while relay R^C is shifting from either extreme position to the other due to 85 reversal of relative polarity of the current 90 in the track rails.

Although I have herein shown and described only one form of signaling system embodying my invention, it is understood 100 that various changes and modifications may be made therein within the scope of the appended claims without departing from the spirit and scope of my invention.

Having thus described my invention, what 105 I claim is:

1. In combination, a relay capable of energization in opposite directions, and having a contact which is closed when the relay is de-energized and is also closed momentarily 110 when the direction of energization of the relay is reversed, a signal comprising a lamp controlled by said contact, and an impedance included in the circuit of said lamp for preventing the lighting of said lamp during 115 reversal of said relay.

2. In combination, a relay capable of energization in opposite directions, and having a contact which is closed when the relay is de-energized and is also closed momentarily 120 when the direction of energization of the relay is reversed, a signal comprising a lamp controlled by said contact, and a reactance included in the circuit of said lamp for preventing lighting of the lamp during reversal 125 of said relay.

3. In combination, a relay capable of energization in opposite directions, a normal contact closed when the relay is energized in one direction, a reverse contact closed when 130

the relay is energized in the other direction, a third contact closed when the relay is de-energized and also closed momentarily when the direction of energization of the relay is reversed, a light signal comprising proceed, caution and stop lamps controlled respectively by the normal, reverse and third con-

tacts of said relay, and a reactance included in circuit with said stop lamp for delaying the lighting of the lamp to full brilliancy, 10 whereby the said lamp does not flash during reversal of said relay.

In testimony whereof I affix my signature.

SAMUEL M. LUCAS.
